UNITED STATES PATENT OFFICE

148,584

DESIGN FOR A BICYCLE

Leon Jay Simon, Detroit, Mich.

Application March 2, 1946, Serial No. 127,038

Term of patent 14 years

(Cl. D90—8)

To all whom it may concern:

Be it known that I, Leon Jay Simon, a citizen of the United States, residing at Detroit, in the county of Wayne and State of Michigan, have invented a new, original, and ornamental Design for a Bicycle, of which the following is a specification, reference being had to the accompanying drawing forming part thereof.

Figure 1 of the drawing is a side elevation of a bicycle embodying my new design.

Figure 2 is a front elevation of the bicycle embodying my new design.

Figure 3 is a vertical sectional view taken on the line 3—3 of Figure 1.

The opposite side of the bicycle to that shown

in Fig. 1 is of the same appearance as the side shown.

I claim:

The ornamental design for a bicycle, as shown and described.

LEON JAY SIMON.
